OPEN-END WRENCH HAVING WEDGY JAWS
AND A RECESSED CONCAVE BIGHT WALLWilbur M. Foor, Shepherd, Mich., assignor to
Blackhawk Mfg. Co., Milwaukee, Wis., a corpora-
tion of Wisconsin

Application December 29, 1951, Serial No. 264,115

2 Claims. (Cl. 81—119)

1

The present invention relates generally to improvements in wrenches, and relates more specifically to improvements in the construction of wedge type open end nut and bolt manipulating wrenches.

The primary object of this invention is to provide an improved spanner or open end wrench in which the jaws are most effectively applicable to nuts and bolt heads at various angles and in cramped quarters, and which is extremely compact but durable in construction.

Open end wrenches of the spanner type having one or more heads provided with rigid or relatively movable jaws, have been in use for many years for the purpose of manipulating polygonal nuts and bolt heads. In order to enable these wrenches to be readily applied to hexagonal as well as square nuts and bolt heads it has been common practice to provide a rounded bottom for each open ended socket; and in order to permit such a wrench to be conveniently manipulated in relatively inaccessible localities it has also been proposed to taper the opposite sides of the jaws and to dispose these wedge surfaces at diverse angles relative to the wrench handle. But in all of these prior open end wrenches, the rounded bottoms of the sockets between the jaws were constructed with straight line transverse generatrices which prevented the jaws from assuming maximum contact with the faces of the nuts or bolt heads unless these jaws were made of considerable length. Such lengthening of the jaws naturally made it necessary in order to provide sufficient strength, to make the open end heads of heavy and bulky construction thus obstructing their use in cramped quarters.

It is therefore an important object of my invention to provide the socket of each head of an open ended wrench, with a transverse concavity between the opposite sides of the head, so that maximum surface contact between the jaws and the work is assured with jaws of limited length and great strength.

Another important object of this invention is to provide an improved open ended wrench head of the unitary type having maximum strength and of minimum size, adapted to be applied to work and conveniently manipulated in exceedingly cramped and relatively inaccessible localities.

A further object of the invention is to provide a simple and inexpensive one-piece spanner wrench having one or more heads flexibly applicable to various types of polygonal nuts or bolt heads and associated with a conveniently manipulatable handle.

2

Still another object of the present invention is to provide an attractive precision wrench of the open end jaw and intervening socket type which can be readily and accurately produced in various sizes and for diverse uses.

These and other more specific objects and advantages of my invention will be apparent from the following detailed description from which it will be noted that the gist of the present improvement is the provision of a spanner wrench head having spaced jaws provided with parallel work engaging surfaces forming an intervening open ended socket the bottom of which has a work receiving concavity disposed transversely of and between the opposite side faces of the head.

A clear conception of the improved structure and of the construction and use of several commercial embodiments of the invention, may be had by referring to the drawing accompanying 20 and forming a part of this specification wherein like reference characters designate the same or similar parts in the various views.

Fig. 1 is a perspective view of a double headed open end wrench having one embodiment of the 25 invention incorporated therein;

Fig. 2 is an enlarged side view of one of the end heads of the wrench of Fig. 1;

Fig. 3 is a similarly enlarged central section 30 through the wrench head of Fig. 2, taken along the line 3—3 of Fig. 2;

Fig. 4 is a perspective view of a double headed open end wrench having another embodiment of the invention incorporated therein;

Fig. 5 is an enlarged side view of one of the end 35 heads of the wrench of Fig. 4;

Fig. 6 is a likewise enlarged central section through the wrench head of Fig. 5, taken along the line 6—6 of Fig. 5;

Fig. 7 is a perspective view of a modified 40 wrench head also embodying the invention;

Fig. 8 is a central longitudinal section through the wrench head of Fig. 7, taken along the line 8—8;

Fig. 9 is a perspective view of a further modified wrench head embodying the invention;

Fig. 10 is a central longitudinal section through the wrench head of Fig. 9, taken along the line 10—10;

Fig. 11 is a view showing the application of 50 the wrench head of Figs. 9 and 10 to a square nut; and

Fig. 12 is a similar view showing the application of the same wrench head to the square nut in work clamping position.

55 While the invention has been shown and de-

scribed herein as having been applied to solid headed wrenches of the wedge or tapered type, it is not intended to unnecessarily restrict the use of the improvements to such wrenches; and it is also contemplated that specific descriptive terms employed herein be given the broadest possible interpretation consistent with the disclosure.

Referring to the drawing and especially to the embodiment of the invention shown in Figs. 1 to 3 inclusive, the double headed open end wrench illustrated therein, comprises an elongated manipulating handle 12 having a spanner head 13 formed integral with each end thereof, each head 13 being provided with a pair of spaced jaws 14 having parallel inner work engaging surfaces 15 and tapered opposite outer side surfaces 16, and also being provided with an arcuately curved concavity 17 disposed between the jaw surfaces 15 and extending transversely across the bottom of the open ended socket 18 so as to connect parallel opposite outer side surfaces 19 bounding the head 13. The entire structure is formed of one piece of durable metal and the jaws 14 are of approximately the same length while the opposed outer surfaces 16 are preferably disposed at an angle of approximately thirty degrees relative to each other, and approximately fifteen degrees relative to the central longitudinal plane of the handle 12 disposed midway between the surfaces 19. The surfaces 15, 16, 19 of each head 13, are preferably plane surfaces, but the surface which forms the concavity 17 is arcuately curved and may be formed in any suitable manner as with the aid of a circular milling cutter revolving about an axis perpendicular to the jaw faces 15.

Referring to Figs. 4 to 6 inclusive of the drawing, the embodiment of the invention shown therein is essentially the same as that of Figs. 1 to 3, except that it has a concavity 27 of slightly different construction, and the side surfaces 19 are of somewhat greater area in order to thicken and strengthen the innermost ends of the jaws 14. In this modified structure, the concavity 27 which spans the space between the outer parallel surfaces 19 of each head 13 at the bottom of the open end socket 18, consists of a conical recess which may readily be formed by running a drill point into the center of the socket bottom midway between the jaw surfaces 15. But in both embodiments the socket bottom may be curved laterally of the jaws 14, and the concavities 17, 27 which extend transversely of the head surfaces 19 should be of considerable depth in order to properly perform their intended functions.

Referring to Figs. 7 and 8 of the drawing, the modified wrench head 13 shown therein is also essentially the same as in Figs. 1 to 3 inclusive, except that the concavity 37 is formed with four flat and angularly disposed bounding surfaces inclined toward the central longitudinal plane of the head 13 and toward the jaw surfaces 15, as well as being inclined inwardly relative to the opposite side surfaces 19. These concavity bounding surfaces may be formed in any suitable manner as by broaching, casting or forging, and are effectively cooperable with square or hexagonal nuts and bolt heads.

Referring to Figs. 9 and 10 of the drawing, the further modification of the invention shown therein, embodies a concavity 41 which is bounded by two flat and angularly disposed surfaces which are inclined relative to each other

and to the head surfaces 19, but are perpendicular relative to the inner jaw surfaces 15 and span the gap between the jaws 14. These inclined surfaces of the concavity 41 may also be formed in any convenient manner as by casting, forging or broaching.

When any one of the improved wrenches illustrated has been properly constructed, the opposite end heads 13 of each wrench should be formed to cooperate with polygonal nuts or bolt heads of different standard widths across flats, and the sockets 18 may be then applied to nuts 21 or to bolt heads with the wrench handle 12 disposed either perpendicular to or at any desired oblique angle relative to the bolt or stud 22. In Fig. 11, a wrench of the type illustrated in Figs. 9 and 10 is shown applied to a nut 21 with the wrench handle substantially perpendicular to the stud 22; whereas in Fig. 12 the same wrench has been applied to the nut 21 at an angle of approximately fifteen degrees relative to the body 23 against which the nut 21 is being clamped.

All of the embodiments of the invention illustrated herein provide for greater contact of the jaw surfaces 15 with the flats of nuts or bolt heads while still permitting the use of jaws 14 of minimum length and thickness and without sacrificing strength in the jaws. The flat surfaces 19 at the inner ends of the jaws 14 also enable the wrench heads 13 to be inserted in limited spaces and manipulated at various angles while still maintaining maximum contact between the jaw surfaces 15 and the work. The concavities 17, 27 of the improved wrenches therefore enable the heads 13 to be constructed of relatively small and compact size without sacrificing strength or gripping or contact area with the work; and the provision of the flat parallel surfaces 19 on the heads 13 and which merge with the tapered jaw surfaces 16 further permits maximum reduction in sizes of the heads 13 without sacrificing strength in the jaws 14.

From the foregoing detailed description of the present improvement, it should be apparent that my invention in fact provides an open end wrench of minimum size and of maximum strength adapted to be readily constructed in various sizes and at moderate cost. The provision of the recess or concavity at the bottom of the open ended socket 18 and between the side surfaces 19 of the heads 13 provides maximum contact area at the work engaging faces 15 of the jaws 14 while maintaining maximum strength of these jaws 14 when operating on different types of nuts 21, and the provision of the parallel opposite side surfaces 19 reduces the wrench thickness to a minimum without affecting the jaw strength. In this respect the improved wrench also differs from all known prior open ended wrenches in some of which tapered outer surfaces of the jaws extended throughout the length of the heads and thus produced more bulky assemblages which could not be readily applied and manipulated in cramped localities. The improved wrenches have proven highly satisfactory and successful in actual use, and may be furnished with either single or multiple heads 13, and with inclined jaw surfaces 16 having various angularities from zero to approximately forty-five degrees relative to each other.

It should be understood that it is not desired to limit this invention to the exact details of construction or to the precise mode of utilizing the unitary open end wrenches herein shown and de-

scribed, for various modifications within the scope of the appended claims may occur to persons skilled in the art.

I claim:

1. In an open end wrench, a unitary work engaging head having a nut-engaging recess formed by spaced jaws extending from a bight portion, said jaws being provided with parallel nut-engaging confronting surfaces and with opposite side surfaces adjoining said confronting surfaces, each of said side surfaces inclining from said bight portion and converging toward free ends of said jaws so as to form an angle of approximately fifteen degrees between a common central plane of the jaws and a plane containing the respective side surface, said side surfaces merging into plane surfaces of said bight portion and the latter surfaces lying on opposite sides of and parallel to said central plane, said bight portion having a concave wall for enlarging said nut-engaging recess, the concavity of said wall extending from one of said confronting surfaces to the other, and said concave wall also containing another cavity which further enlarges said nut engaging recess.

2. In an open end wrench, a unitary work engaging head having a nut-engaging recess formed by spaced jaws extending from a bight portion, said jaws being provided with parallel nut-engaging confronting surfaces and with opposite side

10
15

surfaces adjoining said confronting surfaces, each of said side surfaces inclining from said bight portion and converging toward free ends of said jaws so as to form an angle of approximately fifteen degrees between a common central plane of the jaws and a plane containing the respective side surface, said bight portion having a concave wall for enlarging said nut-engaging recess, the concavity of said wall extending from one of said confronting surfaces to the other, and said concave wall also having another unobstructed concavity midway between said confronting surfaces which further enlarges and increases the depth of said nut-engaging recess at said central plane.
